UNITED STATES PATENT OFFICE.

JAMES F. MARSHALL, OF AUBURN, NEW YORK, ASSIGNOR OF ONE-HALF TO DUNN & McCARTHY, OF BINGHAMTON, NEW YORK, A CORPORATION OF NEW YORK.

SHOE AND METHOD OF MAKING THE SAME.

1,336,784.

Specification of Letters Patent.

Patented Apr. 13, 1920.

Application filed August 5, 1916. Serial No. 113,210.

To all whom it may concern:

Be it known that I, JAMES F. MARSHALL, a citizen of the United States, residing at Auburn, in the county of Cayuga and 5 State of New York, have invented new and useful Improvements in Shoes and Methods of Making the Same, of which the following is a specification.

This invention relates to boots and shoes 10 that have covered heels, and particularly to the method of attaching and covering the heels.

The usual method of providing ladies' boots and shoes with covered heels, usually 15 "French" heels, is as follows. The heels are made by a manufacturer other than the manufacturer of the shoe, and the covers of leather, satin, celluloid, or other thin sheet material, are attached to the heels by 20 the heel manufacturer. The shoe manufacturer, before making requisition upon the heel manufacturer for covered heels, has to estimate the shapes and sizes of the heel-seat portions of the shoes that he expects 25 to make, and the heel manufacturer shapes the heels accordingly, but in the course of making the shoes the heel-seat portions do not always assume the intended shapes. Variations in this respect are brought about 30 by variations in the thickness of the counter stiffeners, in the thickness of the upper-leather, and by non-uniform workmanship in lasting the shoes. Inasmuch as the shape of the heel is predetermined, and the shape 35 of the heel-seat portion of the shoe cannot always be predetermined, the latter has to be fitted to the heel in order to produce a satisfactory finished shoe. The operation of fitting the shoe to the heel is attended 40 by much difficulty and annoyance and in some cases requires much extra time.

The body or blank of a covered heel is usually made of a single piece of wood, the cover is fitted smoothly to its upright 45 surface, and the upper marginal portion of the cover is turned in upon the heel-seat portion of the heel-blank, which has to be dished or concaved to a considerable degree to receive the heel-seat portion of the 50 outsole so that the upper part of the heel-cover and the lower part of the shoe upper will meet in substantially contiguous relation and not expose the edge of the heel-seat portion of the outsole. Furthermore, 55 the marginal portion of the heel-seat por-

tion of the outsole has to be trimmed to a feather edge to permit such meeting of the heel-cover and upper. Such trimming of the heel-seat portion of the outsole requires great care and considerable time, because the bottom surface thereof has to be fitted accurately to the concavity in the top of the heel, for if the outsole is not accurately fitted to the heel the latter will not be rigidly held when it is attached to the 60 shoe.

My present improved method of making a shoe of the character stated enables the shoe manufacturer to attach an uncovered heel-blank in the rough to a lasted shoe, to 70 shape the heel-blank to conform to the heel-seat portion of the shoe, and to attach the heel-cover to the attached heel-blank. The shoe manufacturer is relieved of the necessity of trimming the marginal portion of 75 the heel-seat portion of the outsole to a feather edge, because the upper marginal portion of the heel-cover may be tucked into the crevice between the pulled over portion of the upper and the marginal portion of the outsole. The heel cover is thus utilized to cover the edge of the heel-seat 80 portion of the outsole in addition to covering the heel-blank.

My present improved method reverses the 85 condition of making shoes that have covered heels, in the following respect, to wit,—the heel-blank is trimmed to conform to the predetermined shape of the shoe, whereas according to the method now pre- 90 vailing the shoe has to be made to conform to the predetermined shape of the covered heel. This improved method saves much time in the manufacture of the shoes, dispenses with the necessity of so much care 95 as formerly in fitting one to the other, reduces the cost of the heels, permits the use of heel-blanks made of lifts of leather, leatherboard, or other material than wood, and enables the counter portion of the finished shoe to retain the shape imparted to 100 it by the last. I do not mean to have it understood that my present invention requires a heel-blank made of lifts of leather, leatherboard or other material than wood, for, as 105 a matter of fact, it may be practised with a wood heel-blank, although it would be more economical to use blanks made of such lifts instead of blanks made of wood. The heel-blanks may be attached in the rough, 110

trimmed while attached, and then covered, regardless of the material of which they are made.

Of the accompanying drawings:

5 Fig. 1 represents a side elevation of a boot provided with a covered heel in accordance with the present invention.

10 Fig. 2 represents a vertical section, on a larger scale, of the structure intersected by line 2-2 of Fig. 1.

15 Fig. 3 represents a vertical section similar to Fig. 2, but showing the shoe in an incomplete condition. In this figure a heel-blank in the rough and composed of a plurality of lifts is attached to a lasted shoe and is ready to be trimmed to conform to the shoe preparatory to having the heel-cover attached to it.

20 Fig. 4 represents a face view of a heel-cover of sheet material.

The same reference characters indicate the same parts wherever they occur.

25 In practising my present improved method the upper 10 and insole 11 would be lasted as usual, which operation would include fastening the pulled-over marginal portion 12 of the upper to the heel-seat portion of the insole by lasting tacks 13. The leading ends of these tacks would be 30 turned back and clenched, as shown, by the usual metal plate with which the heel-seat portion of a last is usually provided. I have not attempted to illustrate in detail the component parts of the upper, such as 35 the upper proper, the counter stiffener, and the lining, but it will be understood that these elements conjointly constitute the upper that is indicated at 10 in Figs. 2 and 3.

40 After the upper and insole have been lasted as hereinbefore explained, the next operation would be attaching the outsole 14. The heel-seat portion of the outsole is indicated at 15 in Figs. 2 and 3, and it may be observed, particularly in Fig. 2, which 45 represents the finished shoe, that the marginal portion of the outsole is not trimmed to a feather edge but is of the same thickness as the middle portion. My present method does not call for any departure 50 from the usual method of attaching the outsole excepting, possibly, setting the heel-seat nails 16 a little farther in from the edge of the sole than the distance that might otherwise be considered desirable. 55 The reason for setting the heel-seat nails in from the edge is to leave the marginal portion of the outsole sufficiently free to be pried away slightly from the pulled-over portion of the upper to permit tucking in 60 the upper marginal portion of the heel cover as hereinafter explained.

65 When the outsole has been attached, a heel-blank 17 in the rough may be attached. So far as the fundamental principle of the present method is concerned, it would not

matter whether the heel-blank were made of a single piece of wood or made of a plurality of lifts of other material, but I have shown a heel-blank of the latter form to show as far as possible all the advantages 70 of this method. The heel-nails are represented by dotted lines in Fig. 3 and are indicated at 18. These nails hold the lifts together and are driven through the outsole and insole to attach the heel-blank to the 75 lasted shoe. Although it is customary to support the lasted shoe in an inverted position throughout the operations of lasting, sole laying and heel attaching, I have not attempted to show such position, as it 80 would tend to confuse the observer in view of the other figures of drawing. When the heel-blank has been attached as shown by Fig. 3 it may be trimmed to the desired shape and scoured, and, in the course of 85 the trimming operation, the edge of the outsole would also be trimmed, with the advantage that the heel-blank and the edge of the outsole can be trimmed to conform to the outline of the lasted shoe. 90

Assuming that the attached heel-blank has been trimmed and is ready to receive a heel-cover, the operation of attaching the latter would be the next step. Fig. 4 illustrates a heel-cover of sheet material in a 95 flat condition, but shaped as to outline according to the size and style of heel that it is to cover. One or both confronting surfaces of the trimmed heel-blank and heel-cover would be coated with suitable adhesive substance such as cement, and then the heel-cover would be fitted to the upright surface of the heel-blank so that the curved marginal portion 21 would be in position to be tucked into the crevice between the outsole and upper, as shown by Fig. 2. It would not matter, so far as the principle of this method is concerned, whether the heel-cover were fitted to the upright surface of the heel before the marginal portion 21 is 105 tucked in, or vice versa, the order of performing these two details being optional with the shoemaker. Having fitted the cover 20 to the heel-blank and having tucked in the marginal portion 21 as explained, the next step would be to turn in 110 and fasten, by cement or otherwise, the marginal portion 22 of the heel-cover so that the latter marginal portion would occupy the position shown by Fig. 2. The 115 marginal portions 23 would be turned in against the breast of the heel-blank and would be secured to the latter by cement, and then a breast facing 24, that may be a split portion of the outsole or a separate 120 piece of thin leather, would be secured to the breast and to the marginal portions 23 by cement. The heel would then be ready to receive the usual top lift 25, which would be attached by any suitable means such as 125 130

a screw 26 and nails 27, preferably with the addition of cement to make the seam tight.

In case it is desired to use a heel-blank that has been trimmed to the desired shape 5 and made smooth prior to being attached to the shoe, the procedure hereinbefore described would be varied by omitting the heel-trimming operation. In some cases the trimmed heel-blanks might conform to the 10 lasted shoe so well that no trimming would be necessary after attaching them. In other cases a very slight after-trimming would be sufficient. In every case, however, the shoe maker would be relieved of the necessity 15 of trimming the outsole to a feather edge, and the heel-cover would go over, instead of under, the edge of the outsole.

I claim:

1. The herein-described method of making a shoe, which consists in lasting the 20 upper and insole, attaching an outsole that has an untrimmed heel-seat edge, attaching a heel-blank, trimming said heel-blank and the heel-seat edge of the outsole, and attaching a heel-cover to the trimmed heel-blank and tucking the upper marginal por- 25

tion of such cover between the marginal portion of the heel-seat portion of the outsole and the pulled-over portion of the upper.

2. The herein-described method of making a shoe, which consists in lasting the upper and insole, attaching an outsole, attaching a heel-blank, trimming the attached heel-blank, and attaching a heel-cover to said heel-blank and tucking the marginal portion of such cover between the contiguous heel-seat portions of the upper and outsole. 30 35

3. The herein-described method of making a shoe, which consists in lasting the upper and insole, attaching an outsole, attaching a heel-blank, attaching a heel-cover to said heel-blank, coating the upper marginal portion of said heel-cover with adhesive substance, and tucking said marginal portion between the contiguous heel-seat portions of the upper and outsole. 40 45

In testimony whereof I have affixed my signature.

JAMES F. MARSHALL.
